UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,842, dated November 5, 1895.

Application filed September 30, 1895. Serial No. 564,228. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of flamboyant torch-like ornaments with ornamental scrolls at the base of said ornaments, with sprays of flowers and leaves connected to said torch-like ornaments by bows of ribbon and oval wreaths of small disks at the top of the torch-like ornaments, and festoons of flowers and leaves suspended by ribbons from the torch-like ornaments, as represented in the accompanying drawing.

The border of the design is formed of simi-

lar flamboyant torch-like ornaments with ornamental scrolls and sprays of flowers and leaves on each side of said ornaments, and festoons of flowers and leaves connected by ribbon bows and interlacing with ribbon festoons, and oval wreaths of small disks suspended from said festoons of flowers and leaves, as shown in the drawing.

What I claim is—

1. The design for wall paper herein shown and described.
2. In the design for wall paper, the border herein shown and described.

Witness my hand this 27th day of September, 1895.

CHARLES BOOZ.
